CLAIM

The ornamental design for a robot, as shown and described.

DESCRIPTION

FIG. 1 is a front view of a robot showing our new design;
FIG. 2 is a rear view thereof;
FIG. 3 is a right side elevational view thereof;
FIG. 4 is a left side elevational view thereof;
FIG. 5 is a top plan view thereof;
FIG. 6 is a bottom plan view thereof;
FIG. 7 is a 90-degree front view thereof;
FIG. 8 is a 90-degree rear view thereof;
FIG. 9 is a 90-degree right side devotional view thereof;
FIG. 10 is a 90-degree left side elevational view thereof;
FIG. 11 is a 90-degree top plan view thereof;
FIG. 12 is a 90-degree bottom plan view thereof;
FIG. 13 is a 180-degree front view thereof;
FIG. 14 is a 180-degree rear view thereof;
FIG. 15 is a 180-degree right side elevational view thereof;
FIG. 16 is a 180-degree left side devotional view thereof;
FIG. 17 is a 180-degree top plan view thereof;
FIG. 18 is a 180-degree bottom plan view thereof;
FIG. 19 is a flexed front perspective view thereof;
FIG. 20 is a flexed back perspective view thereof;
FIG. 21 is another flexed perspective view thereof;
FIG. 22 is another flexed perspective view thereof;
FIG. 23 is a flexed top plan view thereof; and,
FIG. 24 is a right side elevational flexed view thereof.
